UNITED STATES PATENT OFFICE.

JOSEPH H. RICHARD, OF MINNEAPOLIS, MINNESOTA.

KNOCKDOWN CABINET.

Application filed June 20, 1922. Serial No. 569,619.

To all whom it may concern:

Be it known that I, JOSEPH H. RICHARD, a citizen of the United States, residing at Minneapolis, in the county of Hennepin 5 and State of Minnesota, have invented a new and useful Knockdown Cabinet, of which the following is a specification.

The device forming the subject matter of this application is a cabinet, adapted to hold 10 a wireless apparatus and a phonograph. The invention aims to provide novel means whereby the instrumentalities above mentioned may be contained and held within a cabinet. Specifically, the invention aims 15 to improve the construction of the cabinet so that it can be taken down, without the use of tools, and be disposed in small compass for shipping.

It is within the province of the disclosure 20 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within 25 the scope of what is claimed, changes in the precise embodiment of the invention shown can be made without departing from the spirit of the invention.

In the accompanying drawings:

Figure 1 shows in vertical section, a device 35 constructed in accordance with the invention; Figure 2 is top plan wherein the lid has been removed, the line 1—1 in Figure 2 indicating the cutting plane on which Figure 1 is taken; Figure 3 is a bottom plan; Figure 4 is a section on the line 4—4 of Figure 2; Figure 5 is a composite perspective view showing one of the joints and attendant parts.

In carrying out the invention there is provided 45 a cabinet including sides denoted generally by the numeral 1. Each side 1 includes a rear post 2 and a front post 3, the lower ends of the posts forming legs 4. The posts 2 and 3 are connected by a top bar 5 and by a bottom bar 6. Panels 7 are mortised at 8 into the bars 5 and 6 and into the posts 2 and 3. Supports 9 are secured to the panels 7. There are openings 10 in the supports 9 and in the front posts 3, the openings being adapted to receive pins 11 or the

like, supporting a vertically adjustable shaft 12.

The back of the cabinet is denoted generally by the numeral 14 and includes a top bar 15 and a bottom bar 16, a panel 17 being mortised at 18 into the top bar and into the bottom bar. As shown in Figure 5, the legs 2 are provided with recesses 19 adapted to receive the ends of the bottom bar 16 of the back 14. The plates 20 of pin hinges are connected to the posts 2 and to the bars 16, the knuckles 22 of the plates 20 being adapted to receive the connecting pins 23. The posts 2 may be cut away as at 24, so as to permit the ready insertion 60 of the pins 23 into the knuckles 22. The top bar 15 of the back 14 is connected in a like way, by pin hinges 21, with the posts 2.

A bottom 25 fits within the rectangle defined by the bars 6 of the sides 1 and the bar 16 of the back 14. The bottom 25 has an opening 45 through which the connections for the wireless outfit is adapted to pass. The bottom 25 carries projecting brackets 26 received in seats 27 formed in 70 the bars 6 of the sides 1 and, thus, the bottom is supported.

A rectangular frame 28 is located in the cabinet adjacent to the upper end thereof, and is provided with projecting brackets 29 received in seats 30 formed in the top bars 5 of the sides 1. Depending U-shaped hangers 31 are shown. The rear arms of the hangers 31 pass upwardly between the rear portion of the frame 28 and the top 80 bar 15 of the back 14. The forward arms of the hangers 31 pass upwardly to the rear of the front portion of the frame 28, as shown in Figure 4. The arms of the hangers 31 are supplied with forwardly extended fingers 32 mounted on the frame 28 and connected thereto by securing elements 33, the construction being such that the hangers may be mounted in adjusted positions on the frame 28, that is, the hangers 100 may be shifted to the right or to the left in Figure 1. In the bottom portions of the hangers 31 there are openings 34 adapted to receive securing elements whereby a phonograph may be mounted on the hangers. The phonograph is shown in dotted line in 105 Figure 1. Although the crank portion of the phonograph is shown in Figure 1 as projecting to the right, for convenience in making the drawing, it will be understood 110

that the phonograph may be mounted in any desired way on the hangers 31. Angle brackets 35 are provided and are connected by screws 36 or otherwise to the panel 17 of the back 14. The angle brackets 35 may be used or omitted at will, but they will be found to be useful when it is desired to support the phonograph on the shelf 12. A lid 37 is connected by pin hinges 38 with the upper ends of the rear posts 2. A prop 41 is hinged to the lid 37 and is adapted to cooperate with a projection 42 on the inner edge of the frame 28, to hold the lid in an open position. Doors 39 are connected by pin hinges 40 to the front posts 3. One of the doors is supplied with a latch 43 adapted to cooperate with the forward portion of the frame 28.

The device is so constructed that it may be set up and knocked down readily. Thus, as shown in Figure 5, the back 14 may be separated from the sides 1, the bottom 25 may be removed, the frame 28 may be detached, the doors 39 may be taken off, the

hangers 31 may be operated from the frame 28, the brackets 35 may be detached from the panel 17 of the back, and the entire structure may be shipped in a flat compact package.

What is claimed is:—

In a device of the class described, a cabinet comprising sides, a back, detachable connections between the sides and the back, a bottom, means for supporting the bottom removably in the cabinet, an upwardly removable open frame seated detachably in the upper end of the cabinet, a depending hanger, and means for supporting the hanger on opposed portions of the frame for sliding movement therealong.

In testimony that I claim the foregoing as my own, I have hereto affixed my signature in the presence of two witnesses.

JOSEPH H. RICHARD.

Witnesses:

FLOYD WELLER,
C. G. GIFFIN.
